[57] ABSTRACT

There is provided a novel Snap Hook of the type commonly known as lanyard hooks having a suspending means readily adaptable for use in key cases.

1
SNAP HOOK

DESCRIPTION OF THE PRIOR ART

Many types of hooks for use in key cases are known as are different methods for suspending such hooks. It has been found that hooks of the lanyard type are particularly favored by ladies for this purpose since keys may be readily inserted in and taken out of such hooks without the danger of breaking or cracking long fingernails. The characteristic of the lanyard hook is that the hook is maintained closed by the outward pressure of one portion of the hook upon the other. This is in contrast to many less expensive types of hooks which are undesirable for the reason stated above and which are kept closed by inward pressure of one member upon the other. The conventional type of lanyard hook is illustrated in Freysinger U.S. Pat. No. 1,648,016 and another somewhat less conventional type of lanyard hook is illustrated in Morehouse U.S. Pat. No. 2,019,691. One of the principle production problems associated with hooks of the lanyard type has been the method of suspending such a hook particularly where it is desired to use it in a key carrying case. Of necessity the lanyard hook in all its variations comprises a substantially flat metal strip bent around upon itself. There is no way to provide it with an integral suspending arm. The suspending means must be separate as is illustrated by the Freysinger and Morehouse hooks referred to above.

It is desirable that the suspending means utilized should make available as many degrees of rotatory freedom as possible. In hooks of the non-lanyard type, it has been found convenient to impact one end of the hook into a head of diameter greater than the wire utilized for the hook itself. Such hooks are illustrated in Zarowin U.S. Pat. Nos. 2,232,503, Reis 2,548,820 and Robinson 2,972,880. As will be clear from an inspection of these devices the solution is not adaptable for use with lanyard hooks since a lanyard hook does not have an available end. Furthermore, such a device may be rotated substantially only in one plane though about two axes.

A partial solution to the problems of fingernail breaking and rotation are offered by Geller U.S. Pat. No. 2,197,218 who utilizes a dumbbell as a suspending means. The Geller solution however is somewhat cumbersome since in order to place a key on a key hook it is necessary to disassemble the entire retaining device, move one end of the dumbbell through a portion of the hook and reverse the procedure. Furthermore, Geller is still limited to rotation in substantially one plane.

A partial solution to the rotation problem is offered by the double loops utilized in the Morehouse clasp, however this necessitates the use of an additional portion in the device and is somewhat cumbersome.

SUMMARY OF THE INVENTION

There is provided a novel hook of the lanyard type in combination with the dumbbell shaped suspending means. The shaft portion of the dumbbell is slideably but irremovably crimped into the upper portion of the lanyard hook. The lanyard hook may rotate around the lower portion of the dumbbell and the upper end of the dumbbell may be retained in a conventional hook retaining means, for example, of the type illustrated in Zarowin, Reis, and Robinson supra but provides a far greater number of degrees of freedom of rotation than are available to the devices of these patents. The device

of the present invention is manufactured in a simple and inexpensive manner. The dimensions of the hook portion of the device are defined upon a flat metal blank. An opening is provided in the central portion of this blank substantially closer to one end than the other, the opening having a first and a second radial extension substantially parallel to the longitudinal axis of the blank. The dumbbell utilized as a suspending means is inserted into this opening which is then crimped to substantially close the radial extensions whereby the shaft portion of the dumbbell is slideably but irremovably retained therein. The rest of the hook is then formed in the conventional manner. Alternatively the hook may be bent in the conventional manner, the dumbbell inserted and the crimping executed as the final step.

DESCRIPTION OF THE DRAWINGS

FIG. 1 shows a plan view of the metal blank utilized to manufacture the hook of the present invention having the outlines of said hook portion delineated thereon.

FIG. 2 is a plan view of the hook portion of the device prior to bending.

FIG. 3 is a plan view of the suspending means of the present invention.

FIG. 4 is a side elevational view of the hook and suspending means, in slightly open position.

FIG. 5 is a top plan view of the device of FIG. 4 omitting the suspending means, viewed at 5-5.

FIG. 6 is an alternate embodiment of the view of FIG. 2.

FIG. 7 is an alternate embodiment of FIG. 4.

DESCRIPTION OF THE PREFERRED EMBODIMENTS

The device of the present invention 50 comprises in essence two parts — a hook portion and a suspending means. For reasons of convenience, although the hook portion is manufactured from a single piece of metal, it is convenient to refer to it as having three separate portions. The hook portion 20 consists of a central portion 11 having a shorter extension 17 and a longer extension 19 extending from the ends thereof. Central portion 11 is bent into the form of a substantially closed loop with shorter extension 17 extending from point 53 divergently from extension 19 extending from point 52. The free end of extension 19 is bent into a U-shape so that end 18 thereof is located outwardly of end 16 of portion 17. Extensions 17 and 19 are so mutually located that end 16 presses outwardly against end 18 and when pressed inwardly will open to provide a space for sliding keys or the like over end 18. When the pressure is released from portion 17 end 16 will again contact end 18, thus closing the gap. The suspending means for the device comprises a dumbbell 30 having ends 32 and 34 connected by shank 36. The diameter of ends 32 and 34 measured perpendicular to the axis of the dumbbell is greater than the diameter of shaft 36 similarly measured. The upper central portion of segment 11 of hook 20 has an opening therein. The diameter of said opening is greater than that of shaft 36 and less than that of head portions 32 and 34 of dumbbell shaped suspending member 30. The shank portion 36 is located within opening 12 in such a manner that head 34 is located within the loop segment of portion 11 defined substantially by points 52 and 53. Shaft 36 is free

to move slideably within opening 12 and also to pivot substantially about head 34. Head 32 is suspendable from any conventional slot type key carrying case. Adjacent to opening 12 are closed radial extensions 14 and 15.

In the process of manufacturing the device of the present invention there is utilized a substantially flat metal blank 10. Upon this blank there is defined the outline of the hook portion 20 having an opening 12 with radial extensions 14 and 15 lying parallel to the longitudinal axis of said blank. While it is possible to define the main portion 20, the opening 12 and the extensions 14 and 15 in a single operation, it is generally preferred to utilize a separate defining operation, suitably a die stamping operation for each definition thus for example one stamping step for the outline of portion 20, a second step for opening 12 and a third step for extensions 14 and 15. The order in which these steps are carried out is not critical. The dimensional relationships between openings 12 and extensions 14 and 15 with the dimensions of head portions 32 and 34 and shank portion 36 of the dumbbell shape suspending member 30 are important. Opening 12 in the initial steps as shown in FIGS. 1 and 2 should be sufficient to permit ends 32 or 34 to pass readily therethrough, however, the width of openings 13 and 15, measured perpendicular to the longitudinal axis shown in FIG. 1 should be chosen so that when the maximum width of 14 or 15 is subtracted from the width of 12 it shall exceed the width of shank 36 but shall be less than the width of head portions 32 and 34. The devices of FIG. 4 may be assembled from the components shown in FIGS. 2 and 3 by one of two routes. In one mode, the hook portion 20 is bent into the general form shown in FIG. 4. The head 34 suspending member 30 is then inserted through opening 12 and a crimping force perpendicular to the longitudinal axis of member 20 is applied to central portion 11 whereby radial extensions 14 and 15 are substantially closed and the width of opening 12 reduced in a manner sufficient to permit shank 30 to move slightly therethrough but heads 34 and 32 are restricted from so doing.

In an alternate mode of proceeding the suspending member is inserted through hole 12 the aforesaid crimping force applied to segment 11 and thereafter the hook portion 20 is bent into the general form shown in FIG. 4. Of these two modes the first is to be preferred.

Two minor modifications of the device are to be considered as within the scope of the present invention.

On one modification, shown in FIG. 7 the hook 120 comprises portion 117 having end 116 thereof slightly off-set at point 121.

In another modification, illustrated by the blank shown in FIG. 6, the radial extensions 214 and 215 of

opening 212 are tapered in the manner shown. In this modification the dimensions are selected so that the diameter of 212 less the width of extensions 214 and 215 where they meet opening 212 yields a dimension which is greater than the axial diameter of shaft 34 and less than the diameter of dumbbell end 32 or 34.

I claim:

1. A suspendable snap hook, comprising: a pivotal, swivel anchor means having a shank portion, a first head portion, and a second head portion;

said first head portion being affixed to one end of said shank portion and said second head portion being affixed to the other end of said shank portion, both of said head members having a maximum thickness when measured perpendicular to the principal axis of said shank member exceeding the thickness of said shank member; and

a hook means comprising a continuous bent strip of resilient metal having a front surface and a rear surface and a pair of parallel sides, said hook means including;

a short segment having a first end and a second end; a long segment having a first end and a generally J-shaped second end; and

a crimped eyelet section, said crimped eyelet section dividing said first end of said short segment from the first end of said long segment;

said hook means further having a substantially pinched, closed loop, figure 8 configuration in which the second end of the short segment and the second generally J-shaped end of the long segment overlap one another and are urged together by the resilience of said metal strip in a substantially face-to-face, opposing relationship;

said crimped eyelet section further including a generally circular opening and a pair of longitudinally disposed radial extensions extending from opposite sides of said opening in a direction substantially parallel to the sides of said continuous, bent strip of resilient metal, the diameter of the opening of said crimped eyelet being greater than the diameter of the shank portion of said anchor means and less than the maximum diameter of either of the head portions of said anchor means; and

said anchor means is slideably and swivelably engaged within said crimped eyelet section, wherein said hook member is suspended from one head member of said anchor means and said remaining head member of said anchor means is anchorable in a suitable external retaining means, and further wherein pressure may be applied to force the smaller section inwardly to open the loop thereby permitting said hook to be releasably attached to suitable small objects.
